LICENSE PLATE AND SIGN

John P. Meehan, Los Angeles, Calif.

Application December 31, 1934, Serial No. 759,911

3 Claims. (Cl. 40—136)

My invention has to do with signs, in its more particular aspects, relates to embossed metal plates such as are used for displaying automobile license indicia. License plates of this type are described in my issued United States Letters Patents Numbers 1,898,379 and 1,899,971.

In the apprehension of criminals, automobile license plates have come to play such an important role that maximum clarity and visibility must be embodied in the plates so that the license characters may be read at a glance. Such devices are, for reasons of economy, necessarily made of relatively thin plates and of light weight materials. Unless such plates have maximum rigidity, the ordinary uses and abuses to which they are subjected cause undulations, distortions and breaks of the plate and enameling, creating illusive reflecting surfaces, particularly in the sunlight or at night when an attempt is being made to read the characters under a ray of light.

An object of my invention, therefore, is to provide a license plate which may be manufactured economically, and in which the characters are so framed and presented in relief as to have maximum clarity and visibility, and at the same time to provide a plate which has maximum rigidity commensurate with the thickness and weight of the metal from which it is made, so as to minimize distortions, marring and breaking and illusions they create.

Thus I provide a license plate having a raised medial field, and in this field the legend and number characters are presented in relief by being embossed from the under side of the field. Around this field I provide an annular bead co-planar with the field but separated therefrom by an annular channel, and an exterior annular flange is provided around said bead. The plate is formed by embossing the flat body from the under side to create the raised bead and raised field, and the medial field portion is embossed from the under side to create the raised characters in the field, so that initially the entire plate may be dipped or otherwise given a single color coat and then the co-planar characters in the field may be given a contrasting color by a single application of a color-coating roller.

In such signs or license plates, the raised field is necessarily of such size in relation to the entire plate, that the apertures provided for taking the bolts by which they are attached to the object or frame upon which they are to be displayed, must be wholly or partially within the area of the field. Thus when the plates are mounted and as the bolt-heads are drawn inwardly by

tightening upon the nuts, the raised field surface around those apertures is drawn inwardly with the bolt-head and this depressing not only breaks the enamel or other color coating, but also materially mars the plate, causes dangerous reflective surfaces and leaves the plate in such condition that subsequent further distortion and damage may easily take place. Therefore, one of the important objects of my invention is to provide a construction in which the attaching bolts may be applied without breaking the enameling on the field or otherwise marring the plate.

Further objects and accomplishments of my invention will become obvious from the following detailed description of a preferred embodiment, in which:

Fig. 1 is a front elevation of an automobile license plate embodying my invention;

Fig. 2 is a vertical section taken on line 2—2 of Fig. 1;

Fig. 3 is a front elevation of an automobile license plate similar to that of Fig. 1 except that the attaching bolt recesses are differently placed; and

Fig. 4 is a vertical section taken on line 4—4 of Figs. 1 and 3.

The numeral 10 designates a metal plate having an elevated field 11 formed medially thereof by embossing the plate from its under side.

Field 11 has raised co-planar characters therein formed by further embossing the field portion of the plate from the under side. Those characters may typically comprise a legend 12 consisting of the name of the state for which the license plate is provided, as well as the year of the license —such, for instance, as "19 California 36", and letters 15 and figures 16 denoting the license number, such, for instance, as "A 345".

Around raised field 11 and separated therefrom by a channel 20, the bottom of which channel 40 is in the plane of the plate body before the embossing is formed, I provide an annular raised bead 21 formed by embossing the plate from the under side thereof, said bead 21 being co-planar with the field 11 but lower than the plane of the raised characters 12, 15 and 16 in the field; and around bead 21 I provide a flat exterior annular flange 25 which is co-planar with the bottom of channel 20.

Thus the combination of the flange 25, bead 50 21, channel 20, raised field 11 and the raised characters 12, 15 and 16 in the field, produce a relatively strong and rigid plate which is not easily bent or otherwise distorted by ordinary abuses, and this combination also produces a much more 55

attractive plate and one in which all of the characters are framed and clearly presented in relief so as to be legible at a glance. Also the indicia characters on such a plate may be contrasted in color from the remainder of the plate by the single operation of passing a color-coating roller over the raised co-planar characters.

Around the edges and within the area of the raised field 11 I provide recesses 30, here shown as four in number, but which number may of course be varied as desired, and through approximately the center of each of said recesses I provide an aperture 31 adapted to pass an attaching bolt having a head or carrying a washer. Recesses 30 are sufficiently larger than the apertures 31 to accommodate the bolt head or washer 32 (see Fig. 4), and since the bottom of each recess 30 is substantially co-planar with the bottom of channel 20, or the lowermost plane of the plate, the raised field surface is not drawn inwardly when the nuts are tightened up on the attaching bolts during mounting, and consequently the field surface is not marred or damaged. While I have described elements 30 as recesses in the raised field, they may be defined also as widened or enlarged portions of the annular channel 20, which widened or enlarged portions project into the field and depress the field to the extent of the projection.

The plate of Figs. 3 and 4 is substantially identical with that of Figs. 1 and 2 except that in Figs. 3 and 4 the recesses or enlarged channel portions here designed as 40 are located one at each corner of the rectangular field, as shown, and an aperture, here numbered 41, is provided through the center of each recess to take the attaching bolt, as is the case in the device of Figs. 1 and 2.

While I have described my invention in its particular adaptation as an automobile license plate, and have resorted to various details of form and

construction in so describing it, it is obvious that my invention may take various other embodiments and details of construction and materials without departing from the spirit thereof.

I claim:

1. In a sign device, a metal plate having: a raised annular portion adjacent its periphery, a raised medial field portion carrying indicia characters, and a depressed channel intermediate said raised portions, the bottom of which channel forms one of the lowermost portions of the plate; said channel having spaced enlarged portions each provided with an aperture adapted to pass an attaching bolt.

2. In a sign device, a metal plate embossed to form: a raised annular bead adjacent its periphery, a raised medial field having indicia characters therein, and an annular depressed channel intermediate the bead and the field, said channel forming one of the lowermost portions of the plate and having spaced enlarged portions through each of which is provided an aperture adapted to pass an attaching bolt, each of said spaced enlarged portions being sufficiently large to accommodate the attaching bolt head.

3. In an automobile license plate, a flat metal body embossed to form a raised rectangular field medially thereof and a raised annular bead separated from the field by an annular channel, raised co-planar indicia characters in the field, and an exterior annular flange around said bead, said field being co-planar with the annular bead and said flange being co-planar with the bottom of said annular channel, and said channel being wider at spaced points therearound, each of which widened portions projects into the field and through each of which an aperture is formed to pass an attaching bolt having a head, each widened portion being larger than its aperture so as to accommodate the bolt head.

JOHN P. MEEHAN.
